(57) **CLAIM**

The ornamental design for an eyeglass frame, as shown and described.

DESCRIPTION

FIG. 1 is a top isometric view of an eyeglass frame showing an embodiment of our new design comprising eyeglass frame arms.

FIG. 2 is a bottom isometric view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a front elevational view thereof.

FIG. 8 is a rear elevational view thereof.

FIG. 9 is a top isometric view of the eyeglass frame according to the embodiment of FIGS. 1–8 but with different environmental structure to illustrate the versatility of the new design.

FIG. 10 is a bottom isometric view thereof.

FIG. 11 is a top plan view thereof.

FIG. 12 is a bottom plan view thereof.

FIG. 13 is a left side elevational view thereof.

FIG. 14 is a right side elevational view thereof.

FIG. 15 is a front elevational view thereof.

FIG. 16 is a rear elevational view thereof.

FIG. 17 is a top isometric view of the eyeglass frame according to the embodiment of FIGS. 1–8 and FIGS. 9–17 but with different environmental structure to further illustrate the versatility of the new design.

FIG. 18 is a bottom isometric view thereof.

FIG. 19 is a top plan view thereof.

FIG. 20 is a bottom plan view thereof.

FIG. 21 is a left side elevational view thereof.

FIG. 22 is a right side elevational view thereof.

FIG. 23 is a front elevational view thereof; and,

FIG. 24 is a rear elevational view thereof.

Stippling and tangency lines in the drawings represent the three-dimensional contours of the design, and are not intended to indicate surface decoration. The broken lines in the drawings are included for the purpose of illustrating unclaimed portions of the eyeglass frame that form no part of the claimed design.
